ROY T. HURLEY, OF DOBBS FERRY, NEW YORK, ASSIGNOR, BY MESNE ASSIGNMENTS, TO MOTO METER GAUGE & EQUIPMENT CORPORATION, OF LONG ISLAND CITY, NEW YORK, A CORPORATION OF DELAWARE

HEAT INDICATOR FOR MOTOR VEHICLES

Application filed June 29, 1929. Serial No. 374,720.

The present invention relates to an improved combined radiator cap and motor heat indicating instrument which is so compact and so arranged that it may be given any type of ornamental form or design in harmony with the lines, form or shape of the motor car to which it is to be applied.

The main object of the present invention is to provide a combined unit of the type described above with means for deflecting light from the exterior to the interior of the instrument so as to illuminate its indicator.

Other objects and advantages of the present invention will be apparent from the following specification and the accompanying drawings which illustrate several embodiments of the present invention.

In the drawings:

Fig. 1 is a longitudinal sectional view of one form of the invention;

Fig. 2 is a partly broken plan view of the same embodiment of the invention;

Fig. 3 is a rear view of the same;

Fig. 4 is a longitudinal sectional view of another embodiment of the invention;

Fig. 5 is a partly broken top view of the same;

Fig. 6 is a partly broken lateral view of another embodiment of the invention; and

Fig. 7 is a plan view of the same embodiment.

In Figure 1 the combined cap and instrument 1 is shown as applied to the neck 2 of the radiator 3 of the motor vehicle. As is well known, the cooling liquid of the motor vehicle is circulated by a pump or by thermo-siphon action, being delivered from the water jackets (not shown) to the upper part of the radiator and being returned from the lower part of the radiator after it has been cooled therein to the lower part of the water jacket. When it is desired to replenish the liquid in the cooling system, the cap 1 is removed from the neck and liquid is poured in. The level to which the liquid may normally rise in the radiator is limited by the provision of an overflow pipe 4, which terminates in an open mouth in the upper portion of the radiator or in the neck. Under ordinary running conditions the water

is at a somewhat lower level than the mouth of the overflow pipe, since some of the water passes out of the pipe when the water surges and some of the water is lost by evaporation.

The particular cap and instrument assembly herein chosen to illustrate the invention, comprises two principal units: an inner shell unit 6, which carries the indicator and the operating mechanism therefor, and an outer shell unit 7 provided with a window 60 and acting jointly with the inner shell to form a housing for the indicator mechanism. The neck 2 of the radiator may be of any form desired and the manner of its engagement with the combined unit 1 may be of any type desired.

In the present embodiment of the invention however, the neck 2 and the combined unit are provided with cooperating members for quickly and conveniently securing the combined unit in place upon the radiator neck. For this purpose the neck 2 may be provided with downwardly extending flanges 11 along the inner edges thereof, these flanges being formed as cams for engagement with cooperating locking arms 12 of a locking member 13 carried by and forming part of the inner shell assembly 6. The specific devices for attaching the combined unit 1 to the radiator or radiator neck, do not constitute a part of the present invention and are merely illustrated to show one manner of mounting and attaching the combined unit which provides for correct orientation of the combined unit with relation to the radiator. It will be observed that the combined unit is so mounted on the radiator or radiator neck that the indicator faces rearwardly of the car so that it may be observed at all times by the operator of the vehicle.

The inner and outer shell units 6 and 7 form the cap proper and carry all of the indicating mechanism and the operating mechanism therefor.

The inner shell member comprises a substantially circular body portion 14, an annular, downwardly extending, continuous flange 15, and a laterally extending horizontal flange 16, which is disposed only a short distance above the top of the radiator 3. The

flange 16 may be provided with an annular raised portion 17 which forms a shoulder 18 designed as a stop and as a rest for the scale plate 19 of the indicator mechanism. The flange 15 is adapted to embrace the neck 2 and the body portion 14 of the inner shell unit 6 is adapted to rest upon a gasket ring 20 which is disposed between the shell unit 6 and the neck 2 so as to provide an effective sealing of the radiator opening. The body portion 14 of the inner shell unit is provided at the center thereof with an interiorly threaded boss 21 designed to receive the operating mechanism 22, which extends downwardly from the body portion 14 of the inner shell unit 6. While the operating mechanism of the heat indicating instrument may be of any type desired, in the form of the invention disclosed herein, the operating mechanism is of the type which 20 results in a variable rotation of the shaft 23 in response to temperature variations of the cooling liquid. Associated with the operating mechanism 22 and fixedly mounted on the shaft 23, is the pointer 24 which extends 25 horizontally from the shaft 23 and rearwardly of the instrument.

The outer end 25 of the pointer is turned downwardly and is adapted to move across the face of the arcuate scale plate 19 and in 30 proximity thereto. Such movement of the pointer is imparted thereto by means of the operating mechanism 22 which rotates the shaft 23 in one direction as the temperature of the cooling liquid rises and in the opposite 35 direction as the cooling temperature falls. The portion 17 of the inner shell is provided with upstanding posts or projections 26, there being three of these posts in the illustrated embodiment. The outward faces of these posts 40 are inclined and therefore serve to support the scale plate 19 in an inclined position. The scale plate is suitably secured to the inclined faces of the posts 26 by cement or in other desired manner. It will be observed that the 45 pointer extends across the upper edge of the scale plate and that the down turned end 25 of the pointer lies in front of the scale plate and extends approximately parallel thereto. The scale plate or dial 19, is preferably made of 50 celluloid or any other translucent material and if desired the down turned end 25 of the pointer and the index marks indicating the upper and lower limits of the safe operating range may be painted with a luminous paint.

55 The present invention, however, embodies means for deflecting light from the exterior to the interior of the unit to illuminate the dial and if desired therefore, the luminous paint may be eliminated.

60 The outer shell unit 7 comprises a circular casing or shell member and is preferably so designed as to provide a closed chamber between the inner and outer shell units for housing the indicating mechanism, the outer shell 7 being also preferably so designed

as to give the chamber a substantially wedge shaped longitudinal cross section. The combined unit is preferably so designed that the deeper portion of the chamber is disposed rearwardly where the indicating dial is 70 placed. The outer shell 7 is assembled with the inner shell 6 by means of the screws 27.

The outer shell is provided at its rearward end with an upstanding wall 28 having a window opening 29. The wall 28 is preferably recessed internally for the reception of the window pane 30 which is formed as a segment of a frustum of a cone. The small retaining plates 31 overlie the inner faces of the ends of the window when they are clamped 80 against the window by screws 32 through the wall and into the plates 31 from the exterior of the wall.

In order to provide for the illumination 85 of the dial 19, the combined unit carries an optical device for deflecting light from the exterior to the interior of the unit in the vicinity of the dial plate 19. The optical device may take any one of a plurality of forms and may be designed so as to deflect light 90 from the sky, from street lights, or from the head lights of on coming vehicles or from any other source.

For this purpose the outer shell 7 is provided with an opening 33 disposed immediately over the dial 19. An optical light deflecting device of any type desired is mounted in the opening 33. In the form shown in Figs. 1, 2 and 3, the optical device 34, is in the form of a triangular prism made of glass 100 or quartz as may be desired and is retained in the opening 33 by means of the strips 35. The outer shell 7 is provided with a forwardly inclined plate 36 immediately adjacent to the opening 33. The plate 36 is provided with a lip 37, which cooperates with the strips 35 to retain the prism 34 in position. The plate 36 also serves as a reflecting backing for the prism 34. While the face 38 of the prism 34 is shown in Fig. 1 as disposed in a vertical position so that it may catch and deflect light from on coming vehicles onto the dial plate 19, it is obvious that the face may be disposed at any angle desired so that it may serve to reflect both light from on coming vehicles and light from street lights or the sky, as the case may be.

In the embodiment of the invention as shown in Fig. 4, the essential difference resides in the fact that the deflecting prism 34' is mounted in such a manner that the light from exterior sources enters the prism through a horizontally disposed face and is then deflected interiorly of the combined unit and in back of the dial plate 19', which is 120 made of celluloid or other translucent material.

This modification also embodies other structural changes among which are the position of the plate 36', which in this construc- 125

tion is disposed interiorly of the combined unit. Another change resides in the fact that the pointer 24' is disposed below the dial 19. The supporting posts 26' which constitute a mounting for the dial 19' are mounted on the main body portion 14' of the inner shell. In other respects the construction and operation of the modification shown in Figs. 4 and 5 is substantially identical with the modification shown in Fig. 1. It will be seen, therefore, that the form of the invention shown in Figs. 4 and 5 will deflect light from the sky or from street lights or the like.

The form of the invention shown in Figs. 6 and 7 is designed to function in substantially the same manner as the form shown in Fig. 1. In this form, however, the optical deflecting device is so disposed that it is protected against possible damage more effectively than in the construction shown in Fig. 1. In this form the optical device comprises a plate 40 of glass or quartz which is disposed on the top of the combined unit and is entirely covered by a metal casing 41 except for its forward edge 42 which is exposed to the light on oncoming vehicles. The rear portion of the plate 40 is curved in the manner shown and projects into the opening 33' disposed immediately above the scale plate 19. It will be seen that in this form of the invention the scale plate 19 will be illuminated by light from on coming vehicles or from any other source which may impinge upon the face 42 of the optical device 40.

It will be seen from the above that the present invention shows a combined radiator cap and motor heat indicating unit which may be observed by the vehicle operator in the daytime as well as at night, the combined unit being provided with light deflecting means to illuminate the scale plate.

While I have illustrated and described in detail certain preferred forms of my invention, it is to be understood that changes may be made therein and the invention embodied in other structures. I do not, therefore, desire to limit myself to the specific constructions illustrated but intend to cover my invention broadly in whatever form its principle may be utilized.

I claim:

1. In a combined radiator cap and motor heat indicating instrument, the combination of an inner shell member adapted to form a closure for the radiator neck, an outer shell member cooperating therewith to form a chamber, an indicating dial in said chamber carried by said inner shell member, operating mechanism carried by the inner shell member, and means carried by the outer shell member for deflecting light to illuminate the indicating dial.

2. In a combined radiator cap and motor heat indicating instrument, the combination

of an inner shell member adapted to form a closure for the radiator neck, an outer shell member cooperating therewith to form a chamber, an indicating dial in said chamber, operating mechanism carried by the inner shell member, and means carried by the outer shell member for deflecting light to illuminate the indicating dial. 70

3. In a combined radiator cap and motor heat indicating instrument, the combination of an inner shell member adapted to form a closure for the radiator neck, an outer shell member cooperating therewith to form a chamber, an indicating dial in said chamber and means carried by the outer shell for deflecting light from the exterior to the interior of the chamber to illuminate the indicating dial. 75

4. In a combined radiator cap and motor heat indicating instrument, the combination of a chamber adapted to form a closure for the radiator neck, indicating mechanism disposed within said chamber, a window in a lateral face of said chamber permitting observation of the indicator, and means mounted on an outer wall of said chamber for deflecting light from the exterior of said chamber to illuminate the indicating mechanism. 80

5. In a combined radiator cap and motor heat indicating instrument, the combination of a chamber having its bottom adapted to form a closure for the radiator neck, a scale plate and pointer disposed within said chamber, a window in said chamber permitting the observation of said scale and pointer, and means mounted on an outer wall of said chamber for deflecting light from the exterior of said chamber to illuminate the indicating mechanism. 95

6. In a combined radiator cap and motor heat indicating unit, a chamber wedge shaped in longitudinal section, adapted to form a closure for a radiator opening and adapted to be mounted on a radiator opening with its greater height facing the rear of the vehicle, a scale plate disposed within the chamber in the rear portion thereof, a window pane in said chamber permitting the observation of the scale plate, and means carried by said chamber for deflecting light from the exterior of said chamber to illuminate the scale plate. 100

7. In a combined radiator cap and motor heat indicating instrument, the combination of an inner shell member adapted to form a closure for the radiator neck, an outer shell member cooperating therewith to form a chamber, an indicating dial in said chamber, said outer shell having an aperture in the top and means mounted in said aperture for deflecting light from the exterior to the interior of the chamber to illuminate the indicating dial. 115

8. In a combined radiator cap and motor heat indicating instrument, the combination

- of an inner shell member adapted to form a closure for the radiator neck, an outer shell member cooperating therewith to form a chamber, an indicating dial in said chamber, said outer shell having an aperture adjacent the indicating dial, and means mounted in said aperture for deflecting light from the exterior to the interior of the chamber to illuminate the indicating dial.
9. In a combined radiator cap and motor heat indicating instrument, the combination of an inner shell member adapted to form a closure for the radiator neck, an outer shell member cooperating therewith to form a chamber, a translucent indicating dial in said chamber, said outer shell having an aperture adjacent the dial, and means mounted in said aperture for deflecting light from the exterior to the interior of said chamber to illuminate the dial.
10. In a combined radiator cap and motor heat indicating instrument, the combination of an inner shell member adapted to form a closure for the radiator neck, an outer shell member cooperating therewith to form a chamber, an indicating dial in said chamber, said outer shell having an aperture adjacent the indicating dial, an inclined metallic plate adjacent said aperture, and an optical prism held in said aperture against said plate for deflecting light from the exterior to the interior of said chamber to illuminate the dial.
11. An ornament supporting radiator cap, wedge-shaped in longitudinal section, and provided with a chamber in the thicker portion thereof, temperature responsive mechanism carried by the cap for exposure to temperature conditions within the radiator, indicating mechanism in said chamber operated by the temperature responsive mechanism, a window in the thicker side of the cap covering the operative range of said indicating mechanism, and means embodied within said cap for deflecting light from the exterior to the interior of the chamber to illuminate the indicating mechanism.
12. The combination with a cap-like member, for mounting on an automobile radiator, having a finished upper exterior surface adapted to be ornamented or to bear ornamentation devices as customarily employed on automobiles, of indicating mechanism, automatically responsive to changing operating conditions, said mechanism being cooperatively associated with said cap-like member, and having peripherally observable indicator means arranged below said finished upper surface to obviate projections or obstructions above said surface, said indicator means comprising a fixed scale plate and a pointer cooperative therewith, and means embodied within said cap-like member for deflecting light from the exterior to the interior of said cap-like member to illuminate the said indicator means.
13. The combination with a cap-like member, for mounting on an automobile radiator, having a finished upper exterior surface adapted to be ornamented or to bear ornamentation devices as customarily employed on automobiles, of indicating mechanism, automatically responsive to changing operating conditions, said mechanism being cooperatively associated with said cap-like member, and having peripherally observable indicator means arranged below said finished upper surface to obviate projections or obstructions above said surface, said finished upper exterior surface being of less height at the center than at the front thereof, a window pane carried by said cap-like member at the front thereof through which the indicator means may be seen, and means embodied within said cap-like member for deflecting light from the exterior to the interior of said cap-like member to illuminate the said indicator means.
14. The combination with a radiator of an automobile, said radiator having a filler spout at the top thereof, of a motor heat indicator mounted on said spout and having a thermally responsive element projecting into said spout, indicating means controlled thereby readable from the driver's seat of the automobile, said indicating instrument being formed to provide a cap for said spout sealing the same against leakage and having parts formed to enclose and substantially conceal said spout, said parts extending into proximity to the outer surface of the radiator, and means embodied within said cap-like member for deflecting light from the exterior to the interior of said cap-like member to illuminate the said indicator means.
15. In a combined radiator cap and motor heat indicating instrument, the combination of an inner shell member adapted to form a closure for the radiator neck, an outer shell member cooperating therewith to form a chamber, an indicating dial in said chamber, said outer shell having an aperture adjacent the indicating dial, an inclined metallic plate adjacent said aperture, and an optical prism held in said aperture against said plate for deflecting light from the exterior to the interior of said chamber to illuminate the dial, said prism having one face exposed to impinging light and another face disposed within said aperture.
16. In a combined radiator cap and motor heat indicating instrument, the combination of, an inner shell member adapted to form a closure for the radiator neck, an outer shell member cooperating therewith to form a chamber, an indicating dial in said chamber, said outer shell having an aperture adjacent the indicating dial, a body of translucent material mounted on said outer shell and having one face exposed to the light of on coming vehicles, and having another face disposed

within said aperture to deflect said light to the interior of the chamber to illuminate the dial.

17. In a combined radiator cap and motor heat indicating instrument, the combination of, an inner shell member adapted to form a closure for the radiator neck, an outer shell member cooperating therewith to form a chamber, an indicating dial in said chamber, said outer shell having an aperture adjacent the indicating dial, an inclined metallic plate extending upwardly and forwardly adjacent said aperture, and an optical prism held in said aperture against said plate for deflecting light from the exterior to the interior of said chamber to illuminate the dial.

18. In a combined radiator cap and motor heat indicating instrument, the combination of, an inner shell member adapted to form a closure for the radiator neck, an outer shell member cooperating therewith to form a chamber, an indicating dial in said chamber, said outer shell having an aperture adjacent the indicating dial, an inclined metallic plate extending downwardly and rearwardly adjacent said aperture, and an optical prism held in said aperture against said plate for deflecting light from the exterior to the interior of said chamber to illuminate the dial.

19. In a combined radiator cap and motor heat indicating instrument, the combination of, an inner shell member adapted to form a closure for the radiator neck, an outer shell member cooperating therewith to form a chamber, an indicating dial in said chamber, said outer shell having an aperture adjacent the indicating dial, a plate of translucent material mounted on said outer shell and having its forward edge exposed to the light of on coming vehicles, and having its rear portion disposed within said aperture to deflect said light to the interior of the chamber to illuminate the dial.

20. In a combined radiator cap and motor heat indicating instrument, the combination of, an inner shell member adapted to form a closure for the radiator neck, an outer shell member cooperating therewith to form a chamber, an indicating dial in said chamber, said outer shell having an aperture adjacent the indicating dial, an inclined metallic plate extending downwardly and rearwardly adjacent said aperture, and an optical prism held in said aperture against said plate for deflecting light from the exterior to the interior of said chamber to illuminate the dial and a metallic cover for said plate.

In testimony whereof I have affixed my signature to this specification.

ROY T. HURLEY.
